DISPLAY BOX

Evelyn G. Levkoff, Rockaway Beach, N. Y.

Application June 13, 1933, Serial No. 675,545

4 Claims. (Cl. 206—44)

This invention relates to improvements in display boxes.

One of the objects of the invention resides in a display box including a body or panel on which advertising indicia may be provided and which supports a pair of compartments at opposite sides thereof in which articles of merchandise may be packed and attractively displayed.

Another feature is the provision of a folding display box embodying a body or panel having compartments swingably mounted at opposite sides thereof and in which merchandise is adapted to be packed, the said compartments being movable to a closed position over the body or panel and held against swinging movement whereby a compact package is provided for the shipping of the box and its contents, and which box may be opened and the compartments swung to a display position beyond opposite sides of the body or panel and the box supported in an upright manner.

Another feature is to provide a display box in which the cover may be swung to a vertical position when the box is opened to extend upwardly from the body or panel to a position coextensive therewith to increase the amount of advertising space, and which cover is rigidly held in such position by props connecting the cover with the spaced display compartments.

A still further object of the invention is to provide a folding display box having the above features of construction which is formed from a single blank of bendable material, and which is simple and inexpensive of manufacture and easy of assembling.

With these and other objects in view, the invention resides in the certain novel construction, combination and arrangement of parts, the essential features of which are hereinafter fully described, are particularly pointed out in the appended claims, and are illustrated in the accompanying drawings, in which:

Figure 1 is a perspective view of my improved display box in closed position.

Figure 2 is a front elevational view of the box with the cover in a raised position.

Figure 3 is a side elevational view of the box shown in the position similar to that in Figure 2.

Figure 4 is a perspective view of the box in open display position.

Figure 5 is a horizontal sectional view on the line 5—5 of Figure 4.

Figure 6 is a horizontal sectional view on the line 6—6 of Figure 1.

Figure 7 is a plan view of the blank from which the display box is constructed.

Figure 8 is a perspective view of a modified form of display box showing the same in open position.

Figure 9 is a side elevational view of the form of box shown in Figure 8 but showing the same in closed position.

Figure 10 is a detail vertical transverse sectional view on the line 10—10 of Figure 8.

Figure 11 is a vertical sectional view on the line 11—11 of Figure 10.

Figure 12 is a perspective view of a further modified form showing the box in an open position, but looking at the rear thereof.

Figure 13 is a front elevational view of the form shown in Figure 12.

Figure 14 is a side elevational view thereof.

Figure 15 is a detail vertical transverse sectional view on the line 15—15 of Figure 12.

Figure 16 is a view similar to Figure 15 but showing the box in closed position.

Figure 17 is a fragmentary side elevational view showing the box in closed position.

Figure 18 is a perspective view of a modified form of closure means for the type of box shown in Figures 1 to 7 inclusive.

Figure 19 is a perspective view of a modified construction of box to that shown in Figures 1 to 7 inclusive.

Referring to the drawings by reference characters, the letter A designates the blank of cardboard or other like bendable material from which the preferred form of my invention is constructed and which form is illustrated in Figures 1 to 7 inclusive.

By reference to Figure 7 it will be seen that the general shape of the blank is substantially inverted T-shaped and includes broadly a transverse section embodying outwardly extending wings B and C and an angularly extending vertical section D. The transverse section of the blank is scored vertically on the lines 10 and 11 to provide a flat body or panel 12. The wing extensions B and C are cut and scored identically so that a description of one will suffice for the other. Each wing extension is scored vertically on the lines 13, 14, 15 and 16. The material between the score line 13 and the score line dividing a side of the body or panel 12 constitutes one of the side walls of a display compartment and which wall is identified by the numeral 17 whereas the areas between the fold lines 13 and 14, 14 and 15, and 15 and 16 provide side walls 18, 19 and 20 respectively for cooperation with the side wall 17.

in order to provide a four wall display compartment when the blank is in set up position. The end of each wing extension of the blank constitutes an attaching flap 21.

5 The wall 18 is provided with a display opening 22, as the said wall 18 constitutes the front wall for the display compartment when the box is set up and opened to a display position.

Extending from the bottom edges of the walls 10 17 and 19 are bottom flaps 23 and 24 respectively which are foldable inwardly to provide a bottom wall for the display compartment, whereas extending from the wall 20 is an outer bottom flap 25 terminating in a locking tongue 26. The flap 15 25 is foldable over the inwardly foldable flaps 23 and 24 when the blank is set up, and the tongue 26 is insertible within the display compartment to form a rigid bottom therefor.

A longitudinal score line 27 extends across the 20 top of the body or panel 12 and terminates at the vertical fold lines 13—13 of the wing sections B and C. The extension section D of the blank A is provided with a score line 28 which is parallel to the score line 27 and which line 28 25 extends to the edges of prop flaps 29 and which flaps are coextensive with the upper edges of the walls 17 of the display compartments. The extension section D is scored on the vertical lines 30 and 31 which are a continuation of the vertical score lines 10 and 11. The score lines 30 30 and 31 and 27 and 28 divide the angular extension D of the blank into an end fold or wall 32 and a cover 33, the extreme end of the cover being scored transversely as at 34 to provide a locking flap 35, the said flap being provided with a central inwardly extending notch 36.

The prop flaps 29 are provided with angular score lines 37 which extend diagonally and outwardly from the upper corners of the body or 40 panel 12 to the outer edges of the said flaps.

In the assembling of the display box, the blank A is of course folded on the respective fold or score lines, each wing section B and C being so folded as to provide a compartment E, the walls 45 17, 18, 19 and 20 forming a compartment E, the walls 17, 18, 19 and 20 forming a rectangular shaped structure and which is held in an erected position by adhesively securing the flap 21 to the back of the body or panel 12. The flaps 23 50 and 24 forming the inner bottom wall are folded in a manner already mentioned and held closed by the outer flap 25 and locking tongue 26. By reference to Figure 4 of the drawings, it will be seen that the display compartment E may be 55 swung to a position forward of and beyond opposite sides of the body 12 and the said compartments are of a size to completely overlie the panel 12 when the same are folded inwardly to closed position as shown in Figure 2 of the drawings.

The prop flaps 29 extend forwardly when the compartments E are in open display position but upon swinging of the compartments E to closed position, the said prop flaps 29 lie flat 60 against the cover 33 and end walls 32. These props serve to support the cover section 33 in an elevated position when the compartments E are in display position and the said cover 33, wall 32 and panel 12 may have advertising indicia printed thereon for the advertising of merchandise adapted to be packed and displayed within the compartments E.

During shipment of the display box with the merchandise contained within the compartments 75 E, the said compartments are swung over the

body 12 in the manner shown in Figure 2, at which time the prop flaps 29 lie flat against the cover 33 and wall 32. By folding the cover downwardly over the compartments E, the wall 32 provides an end wall for the box whereas the 5 cover 33 overlies the compartments E, the flap 35 is inserted between the bottom flaps of the compartments E, the notch 36 thereof receiving the adjacent sides of the two compartments and the box locked in closed position. Thus the box 10 will resemble an ordinary rectangular shaped cardboard box, but by swinging the cover 33 to an open position and moving the compartments E outwardly to the position shown in Figure 4, the shipping box may be transposed into an attractive display stand for the display merchandise packed and shipped therein.

In the drawings, I have shown the two compartments E as having a combined width equal to the width of the front panel 12 as best seen 20 in Figure 2 whereupon, when the same are swung to a closed position, the sides having the display openings 22 therein are in meeting engagement. This prevents the contents of the compartments from accidentally dropping through the open 25 sides during shipment or handling when the box is filled and while in a closed position. However, there may be times when the combined width of the compartments is less than the width of the panel 12 and to close such compartments by 30 swinging them to the front side of the panel as just described would not cause them to assume a position in meeting engagement, thus there is a danger of the contents of the compartment becoming accidentally displaced through the 35 openings 22. Therefore, instead of swinging the compartments to a closed position against the front side of the panel 12, I am able to swing them so that the closed backs of the compartments flatly engage the back of the panel 12 with 40 the open sides of the compartments facing outwardly. The props 29 when the compartments are in this position, extend straight out from the rear of the panel as they do from the front in the position shown in Figure 4, but the compartments have already been folded flat against the rear of the panel, so that it is impossible to fold the props flat against the rear of the panel. Therefore, I provide the diagonal score lines 37 45 which enables the infolding of the props to permit of the folding over of the cover 33 about the open sides of the compartments.

In Figures 8 to 11 inclusive, a modified construction of my invention is shown and which is substantially identical to that shown in the preferred form with the exception that an extra display compartment is embodied therein. In view of the similarity between this form and the preferred form, like reference characters referred to in the preferred form designate similar parts in this modification. In this form of the invention, the bottom of the front wall 12 has an extension portion integral therewith which is folded into a rectangular shaped tray or display compartment 38, the same being of a width approximating the width of the panel 12, and being disposed below the plane of the bottoms of the compartments E. The walls of the compartment 38 are held together by a locking tongue 39 formed on the free end of the extension which passes through a slot 40 provided in the body or panel 12. The front wall of the compartment 38 is provided with slots 41 which receive the locking tongue 35 of the cover when the said cover is in closed position. In the closing of this type 50 55 60 65 70 75 80 85 90 95

of display box, the compartments E fold inwardly over the body 12 in the manner described in the preferred form whereas the cover is locked by engagement with the front wall of the compartment 38. The compartments E serve to close the top of the compartment 38. The compartment 38 acts as a base for the box when in open display position, and the open box is balanced by reason of an equal amount of merchandise contained within the respective compartments.

In Figures 12 to 17 inclusive, a still further modified form is shown and which is substantially the same as the construction shown in the preceding forms with the exception that the panel 12 is provided with a display opening 42, and the bottom of the panel 12 is provided with an extension which is folded into a swingably mounted compartment or tray 43. When in operative position, the compartment or tray 43 is swung to a position behind the panel 12 as shown in Figures 12 and 15, whereas articles of merchandise placed within the compartment 43 may be displayed through the window opening 42. When not in use, the compartment 43 is swung around to the front of the panel 12 as illustrated in Figure 16 and the cover swung to a closed position so that the locking tongue 44 thereof is insertible in a slot 45 provided in a wall of the compartment or tray 43 as will be seen by reference to Figure 17 of the drawings.

In Figure 18 of the drawings the construction is identical to that shown in the preferred form with the exception that the cover 33' is shorter in length and provided at its outer free edge with locking tongues 46 which enter slots 47 provided in the walls of the compartments E. Thus when the compartments are swung to closed position, the cover 33' is swung thereover and the tongues 46 inserted to the respective slots 47.

In Figure 19 a display device is shown which is similar in construction to that shown in the preferred form but is not foldable into a self closed box. The compartments F may be swung to a position over the body 12' but the upper portion of the body is left unscored so as not to fold over the compartments F when they are in closed position. After the compartments F have been swung over the body 12' the entire structure may be inserted in a tubular wrapper for shipment.

In all of the forms shown and described, the display compartments are movable from a position against the flat body of the device to a display position beyond the same, and when in open display position, the compartments serve as a rigid base for supporting the display device in display position. The weight of the articles on the display contained with the display compartment serves to render the box firm and stable and prevents accidental tipping of the structure.

While I have shown and described what I deem to be the most desirable embodiments of my invention, I wish it to be understood that certain changes as come within the scope of the appended claims may be resorted to if desired.

Having thus described the invention, what I claim as new and desire to secure by Letters Patent is:—

1. A display box comprising a body, compartments swingably connected to opposite sides of

said body for inward swinging movement to a closed position thereagainst and to an open display position therebeyond, a cover carried by said body and foldable over the tops and one of the sides of said compartments when the same are in closed position and adapted to assume a raised position coextensive with said body when said compartments are in open display position, and foldable props between said cover and said compartments, the same being foldable to an inoperative position flat against said cover when said compartments are swung to closed position, said foldable props being movable to an operative unfolded position upon swinging of said compartments to open display position for supporting said cover in a raised position.

2. A display box comprising a flat body, display compartments swingably connected to opposite sides of said body for inward swinging movement to a closed position thereagainst and for outward swinging movement to an open display position therebeyond, a display panel hinged to the top of said body, and foldable props connected to opposite sides of said display panel and to the top of the side walls of the respective display compartments, said props foldable inwardly to lie flat over said display panel when the display compartments are in closed position and extending at right angles thereto when said display compartments are in open unfolded position for supporting said display panel in a raised position.

3. A display box comprising a single blank of material cut and scored between its side ends to provide a flat body portion, the material at opposite sides of said body portion being folded into two sets of vertical compartment walls, the extreme side ends of the materials being adhesively secured to the rear of said flat body portion, flaps folded inwardly from the bottom of certain of said vertical compartment walls and forming bottom compartment walls, a foldable cover flap coextensive with the top of said body portion, and foldable prop flaps connecting said cover flap with adjacent vertical compartment walls.

4. A cardboard display box comprising a flat body, box sections swingably connected to opposite sides of said body for inward swinging movement to a closed position thereagainst and to an open display position therebeyond, a cover swingably connected to the top of said body and being scored transversely to divide the same into two cover sections, one cover section adapted to overlie the tops of the box sections when closed and the other cover section adapted to overlie the sides of said box sections when closed, prop flaps hinged to opposite sides of said cover, and to the tops of the inner sides of said box sections, and score lines extending transversely across said prop flaps from the outer edges thereof to the transverse score on said cover, and diagonal score lines extending from the outer edges of said flaps to the hinged connection between said cover and said flat body respectively to facilitate the inward folding of said flaps against said cover and the subsequent swinging of said cover to a closed position over the closed box sections.

EVELYN G. LEVKOFF.
